PANTS

Dorothy L. Miller and Stanton A. Miller, Casper, Wyo., assignors of twenty-five per cent to Sally Jourgensen and twenty-five per cent to John L. Jourgensen

Application February 23, 1949, Serial No. 77,944

2 Claims. (Cl. 128—287)

1

This invention relates to pants and more particularly to infant's pants for covering and holding a diaper.

An object of the invention is to provide an improved pants for holding an infant's diaper which will be cheap and easy to manufacture, efficient in use, easy to put on and take off and comfortable to wear, with a snug fit free of binding.

Still another object is to produce a pants for diapers which is so constructed that the diaper will be properly held without sagging and "wadding up."

A still further object is to produce diaper holding pants that will permit ventilation and yet will not gap or bag at its edges adjacent the crotch so leakage could easily occur.

The exact nature of the present invention, as well as other objects and features thereof, will become apparent from the following description when considered in connection with the accompanying drawings showing pants embodying the invention and especially designed for an infant and capable of acting as a diaper cover, in which:

Figure 1 is a perspective view of the present infant's pants having a diaper associated therewith and partly conditioned in the form it assumes when placed and secured on the infant.

Figure 2 is an inside plan view of the pants in flat condition.

Figure 3 is an enlarged longitudinal section, partly broken away, taken on the line 3—3 of Figure 2.

Figure 4 is a plan view of a conventional diaper that may be folded for use with the pants of Figure 2, as generally shown in Figures 1 and 3.

Figure 5 shows the diaper of Figure 4 folded for use with the pants of Figure 2.

Figure 6 shows the folded diaper of Figure 5 with its ends turned onto the body portion thereof, as practiced when said diaper is associated with the pants as shown in Figures 1 and 3.

Figure 7 is a plan view of a special readily disposable diaper that may be employed with the pants of Figure 2 instead of an ordinary diaper.

Figure 8 shows the disposable diaper of Figure 7 with its ends turned onto the body portion thereof as practiced when said disposable diaper is associated with the pants of Figure 2.

Referring in detail to the drawings, the numeral 5 indicates the pants and diaper holder, the same being in the shape of an isosceles trapezoid with parallel end edges 6 and 7 of unequal length and nonparallel side edges 8 and

2

9 of equal length. The pants or holder when made for an infant and to be used as a diaper cover is constructed of a piece of lightweight non-elastic water-proof material 10, such as, for example, that known as "Koroseal." The ends of the piece of material are folded and stitched to form reinforced end edge portions 11 and 12, and the side edges of such piece of material being gathered as at 13, and reinforced by stitching bindings 14 of a similar material thereon. The pants are of such width at the wider end edge portion 11 thereof as to completely encircle the girth of the infant, that is the infant's body at the waistline and have its ends overlap in a criss-cross manner at the front of the infant's body. The intermediate portion of the pants being passed forwardly at the crotch, the narrow end portion thereof being brought upwardly at the front of the infant's body and the narrow end edge portion 12 being detachably secured to the ends of the wider end edge portion 11 by means of snap fasteners including two male members 15 attached to each end of said edge portion 11, and co-acting female members 16 attached to the edge portion 12. This leaves the pants open at the sides substantially from top to bottom to provide for ventilation and ample leg room for comfort and freedom of movement.

Diaper retaining straps 17 and 18 extend across the ends of the pants at the inside thereof adjacent and inwardly of the end edge portions 11 and 12, the ends of said straps being stitched or otherwise attached to the sides of the pants within the bindings 14, and the portions of said straps between said bindings being unattached to the pants. In practice, a diaper 19 is laid on the inner surface of the pants with its ends extended under and outwardly beyond the straps 17 and 18, whereupon the ends 20 and 21 of the diaper are turned about said straps onto the body portion of the diaper so that the latter is effectively held in place when the pants are placed and fastened on the infant.

As shown in Figures 4 to 6 inclusive, an ordinary oblong diaper 22 may be used with the pants by centrally folding said diaper along the transverse line 23, then folding the superimposed portions 24—24, 25—25 along lines 26—26 and 27—27 onto the superimposed triangular portions 28—28 so as to produce a kite-shaped pad as shown in Figure 5, having the end 20 composed of the superimposed portions 29—29 and the opposite end 21 formed by folding on the line 30.

A readily disposable diaper 31 of the form shown in Figure 7 may be used with the pants instead of the ordinary diaper. Such diaper 31 may consist of laminated sheet of cellulose fibre or like soft material having a body portion 32 of the same shape as but slightly smaller than the pants, and flaps 33 and 34 on the ends of the body portion 32 adapted to be folded on the lines 35 and 36 as shown in Figure 8 over the straps 17 and 18.

From the foregoing description, it is believed that the construction, manner of use and advantages of the present invention will be readily understood and appreciated by those skilled in the art. Minor changes in details of construction are contemplated, such as fairly fall within the spirit and scope of the invention as claimed. It will be particularly noted that the pants are constructed in a very simple manner and thus the cost of manufacture will be low. In the infant's pants shown and described in detail, the pants, outside of the diaper retaining straps, are made from a single piece of material. This piece will be of regular shape and, therefore, there will be no wasted material during cutting. Because of the construction of the pants, they will be snug fitting around the leg and particularly on the inside portion of the leg or that portion adjacent the crotch. This is important, particularly when the pants are constructed for covering diapers. It is also to be noted that the pants, although fitting snugly to the legs, will not bind. The legs of a person, when moved with respect to the body, mostly swing upwardly toward the front of the body. In the pants, as constructed, the leg openings are so arranged that the upper parts thereof extend upwardly toward the front of the pants instead of extending upwardly at the side of the pants. Consequently these upper parts of the openings will be in line with leg movement and there will be no binding. The leg opening arrangement results from having the overlapping of the ends of the piece of material at the front of the pants when the pants are being worn. Another feature of the pants which results in a snug fit is the securing of each of the overlapping parts of the ends at spaced points. The overlapping results in snug fitting and the spaced securing points insure that the proper overlapping is retained so that the snug fitting will always be maintained. Also, with the gathering along the central part of each side edge binding 14, there will be developed sufficient room for receiving the diaper.

Having described the invention, what is claimed as new is:

1. A diaper holder comprising a single sheet of flexible non-stretchable material having such length as to extend from the waistline at the back of an infant wearer through the crotch to the waistline at the front of the infant wearer, said sheet being of greater width at one end than at the other with both ends being constructed to be non-stretchable when the holder is being worn or not worn and the sides of said sheet being of equal length, said sheet from the narrower end to the wider end having substantially straight side edges and gradually increasing in width with no width intermediate the ends being less than the width at the narrower end, bindings stitched to the edges of the sides, the end having the greatest width forming in a non-stretchable condition the back top of the holder and the end of lesser width forming the front

top of the holder when it is being worn, said end of greatest width being of such linear dimension for the particular size of infant for which the holder is designed as to be substantially greater than one-half the girth of the infant at the waistline in order to extend onto the abdomen of the infant and said end of lesser width being of such linear dimension as to be less than one-half the girth of the infant at the waistline but 10 at least of such length as to overlap a substantial distance in criss-cross manner at both sides of that end of greatest width when the pants are to be worn, said criss-crossing beginning on the top of the thigh of the wearer, and snap fastening means for detachably securing the two overlapping parts of the ends together within the length of the overlapping, said snap fastening securing means providing two spaced points of 15 securing for each overlapping part with the cooperating snap elements being along the end marginal edges only and wholly within the substantially straight line extending along the side edges of the sheet forming the holder in order to thereby leave the side edges of equal length 20 entirely free of securing in between the ends of the sheet, each said free side edge notwithstanding the overlapping relation providing, when the holder is worn, a slit opening between the criss-crossing portions forming the overlap and extending from the top of the thigh of the infant upwardly and inwardly toward the front of the abdomen to a point inwardly of the infant's hip bone, said spaced securing means also insuring that the ends of said edges will be held 25 at the waistline at the front of the infant during any leg movement and that the side edges at the inside of the legs will remain snug against the leg but free of binding action.

2. An infant's diaper holder comprising a single piece of waterproof material having a substantially isosceles trapezoid form with all edges straight and provided with reinforced parallel end edge portions of unequal length and reinforced non-parallel side edge portions of equal length with the material being gathered to the reinforcement over the central part of the side edge portions, all said edges being non-stretchable when the holder is being worn or not worn, said piece of material being of such width at the wide end edge portion thereof forming in a non-stretchable condition the back of the holder as to extend substantially more than half way around the infant's body at the waistline for the particular size infant for which the holder is designed and of a width at the narrower front end portion substantially less than half the distance around the waistline of the infant but capable of overlapping the sides of the wider end edge portion upon placing the intermediate portion of the piece of material at the crotch of the infant and the end edge portions at the back and front of the waistline, said overlapping being in criss-cross manner with greater extent of criss-crossing as such approaches the end edges at the waist line, and snap fasteners for detachably securing the narrow end edge portion outside of and to the wider end edge portion at the overlapping, said snap fasteners being within the distance of overlapping and at the waistline and comprising a snap fastener element at the end edge adjacent each side of the narrow and wider end portions and snap fasteners at a point inwardly thereof and also adjacent the end edge only so that said holder will be free of any secure-

ment between the non-parallel side edge portions of equal length, each said free side edge notwithstanding the overlapping relation providing, when the holder is worn, a slit between the criss-crossing portions forming the overlap which is open from the top of the thigh of the infant upwardly and inwardly toward the front of the abdomen to a point inwardly of the hip bone, said holder construction and fastening arrangement also insuring that the ends of the free edges will be held at the waistline at the front of the infant and that the side edges at the inside of the legs will remain snug against the legs and free of binding action, and diaper retaining straps at the inside of both the wider and narrower end edge portions and inwardly of the edges thereof.
